US00D980105S

(12) **United States Design Patent** (10) **Patent No.:** **US D980,105 S**
(45) **Date of Patent:** **** Mar. 7, 2023**

(54) **WATCHBAND LENGTH ADJUSTER**

(71) Applicant: **Shenzhen Xingyi Technology Co., Ltd.**, Shenzhen (CN)

(72) Inventor: **Zhou Yang**, Shenzhen (CN)

(**) Term: **15 Years**

(21) Appl. No.: **29/842,980**

(22) Filed: **Jun. 17, 2022**

(51) LOC (14) Cl. **11-01**

(52) U.S. Cl.

USPC **D11/3**

(58) **Field of Classification Search**

USPC **D11/1-5, 86; D10/32**

CPC **A44C 5/0053**

See application file for complete search history.

CLAIM

The ornamental design for a watchband length adjuster, as shown and described.

DESCRIPTION

FIG. 1 is a top right perspective view of a watchband length adjuster showing my new design;

FIG. 2 is a lower left perspective view thereof;

FIG. 3 is a front elevational view thereof;

FIG. 4 is a partial enlarged view of FIG. 1;

FIG. 5 is a partial enlarged view of FIG. 2; and,

FIG. 6 is a partial enlarged view of FIG. 3.

The broken lines in the figures are for the purposes of illustrating portions of the watchband length adjuster, which form no part of the claimed design.

1 Claim, 6 Drawing Sheets
